COMBINED BOTTLE AND DISPENSER CAP

William Stark, Elmhurst, Ill.

Application November 27, 1957, Serial No. 48,697

Term of patent 14 years

(Cl. D58—7)

Fig.1

I claim:

The ornamental design for a combined bottle and dispenser cap, substantially as shown.
